UNITED STATES PATENT OFFICE.

CHARLES A. LINDSTRÖM, OF ALLEGHENY, PENNSYLVANIA, ASSIGNOR TO
THE PRESSED STEEL CAR COMPANY, OF PITTSBURG, PENNSYLVANIA,
A CORPORATION OF NEW JERSEY.

CAR-DOOR MECHANISM.

No. 805,920.

Specification of Letters Patent.

Patented Nov. 28, 1905.

Application filed October 19, 1904. Serial No. 229,119.

To all whom it may concern:

Be it known that I, CHARLES A. LINDSTRÖM, of Allegheny, Allegheny county, Pennsylvania, have invented a new and useful Car-Door Mechanism, of which the following is a full, clear, and exact description, reference being had to the accompanying drawings, forming part of this specification, in which—

Figure 1 is a side elevation showing part of the car partly broken away illustrating my car-door mechanism. Fig. 2 is a plan view of a portion of the car. Fig. 3 is a vertical cross-section on a larger scale, the sectional plane being on the line III III of Fig. 1. Fig. 4 is a detail view showing in side elevation the arm member or segment which forms part of the car-door mechanism. Fig. 5 is a section on the line V V of Fig. 4, and Fig. 6 is a section illustrating a modification of the device shown in Figs. 4 and 5. Fig. 7 is a detail view of the clevis and equalizer, and Fig. 8 is a modification thereof.

My invention is designed to provide an improved car-door mechanism for operating the doors of railway-cars. It permits the ready opening and closing of the doors, and when the doors are completely closed the mechanism is automatically locked—that is to say, it is placed in such position that the weight of the load which rests on the doors will not tend to open the doors should the hand-actuating mechanism become disengaged from its locking device.

The apparatus is extremely simple and is well adapted to withstand the rough usage and shocks to which the parts of a car are subjected when in use. The working parts are also entirely separated from the load of the car and cannot be deranged thereby.

In the drawings, 2 represents the hopper of a car.

3 are the discharge-chutes of the hopper, and 4 are the doors, which are pivoted at 5. Two sets of doors 4 are preferably connected together by transverse beams 5, so that the corresponding doors of each pair will operate in unison, though this feature is not necessary to my invention, which can be applied to the operation of only a single set of doors.

If desired, the transverse beams 5 can be dispensed with and the doors 4 be one continuous door connected with arms or links 18. Between the pairs of doors 4 and between the

center sills 6 I place the door-operating mechanism. This consists of a quadrant 7, attached to or made integral with a sprocket-wheel 8. The arm 7 is preferably made in segmental form and in the shape of a quadrant, and in the preferred construction (shown in Figs. 4 and 5) the casting, of which the sprocket and segment form part, has a branch 9, trunnions 10 in line with each other being applied to the sprocket and said branch and the whole forming a U-shaped or open casting within the cavity 11, of which the operating-arms described below will freely pass. The trunnions 10 are pivoted in opposite brackets 12, which are fixed to the center sills. Within the scope of my invention the branch 9 and its trunnion 10 may be dispensed with, in which case, as shown in Fig. 6, the device would be pivotally supported solely by the trunnion 10 of the sprocket-wheel 8 at one side only of the space between the center sills. This construction, like that of Figs. 4 and 5, affords a clear space 11 for the motion of the door-operating arms or links.

The sprocket-wheel 8 is rotated by a sprocket-chain 13 from a sprocket-wheel 14 and shaft 15, journaled to a suitable part of the car-body and provided with a locking-ratchet 16 and pawl 17. Within the scope of my invention, as broadly claimed, this sprocket may be substituted by a worm-shaft, in which case the wheel 8 would be a worm-wheel; but the construction shown in the drawings is much preferable. The doors or the beams 5, which connect the doors of the adjacent pairs, are provided with arms 18, which are directly connected at their upper ends by an equalizing-bar 19, attached in turn by a chain 20 to the arm or segment 7, the point of attachment being shown at 21 and the extremity of the segment being indicated at 22. Chains may be used in place of the arms 18; but the arms are preferable, and I intend to make specific claim thereto. Between the equalizing-bar 19 and chain 20 is a clevis 23, connected to the equalizing-bar by a pin 24. This pin extends through both sides of the clevis, and it forms trunnions which rest upon projections or lugs 7 on the segment 7. The purpose of this is to take the load off the chain when the doors are closed, and thus to prevent accidental opening of the doors in case the chain should break.

In Fig. 1 the doors are shown in closed position in full lines. In this position the point of bearing 22 of the chain 20 on the arm 7 at 22 is past the vertical line X X, which passes 5 through the axis 10 10 of the segment, so that the down pressure of the load on the doors will not tend to rotate the segment in the opening direction, which is indicated by the arrow, and therefore will not tend to open 10 the doors, and as the arms 18 rest against the inner face of the segment 7 the mechanism cannot revolve farther in the opposite direction of the arrow. The doors are thus securely and automatically locked in position. 15 To open them, the pawl 17 is released and the shaft 15 is turned so as to rotate the sprocket-wheel 8 and segment 7 in the direction of the arrow. When the point of bearing of the chain 20 on the arm 7 passes the vertical central line X X, the doors will be unlocked and 20 will descend freely by gravity into the open position. (Indicated by dotted lines in Fig. 1.) To close the doors, the shaft 15 is rotated in the reverse direction, thus turning the 25 sprocket-wheel 8 and segment 7 so as to wind up the chain 20 and to elevate the equalizing-bar 19 and arms 18 with the doors, which are finally brought to the closed position. (Shown by full lines.)

30 The use of the equalizing-bar insures perfect closing of both doors, each of which in this respect will act through the equalizing-bar in a manner independent of the other. In the lifting motion of the doors one of the 35 links 18, as shown in Fig. 2, passes freely beyond the central axis 10 of the arm 7. This is permitted in the construction shown in Fig. 5 by the intermediate space 11 and in the construction shown in Fig. 6 by the corresponding space 11', which permit free passage of the connections unrestrained by the sprocket-wheel or the segment-arm.

I claim—

1. In car-door-operating mechanism, a rotatable operating member, links connected to the doors, an equalizing-bar for said links and means adapted to raise the equalizing-bar to a locking position on the operating member, substantially as described.
2. Car-door-operating mechanism comprising a rotatable operating member, a plurality of links, and an equalizing-bar for said links, one of said links being adapted to pass the

axis of the operating member when the doors are operated; substantially as described. 55

3. Car-door-operating mechanism comprising a circular arm or segment, an equalizing-bar, means for raising the equalizing-bar to a locking position on said arm and a plurality of links connecting the equalizing-bar to the doors; substantially as described. 60

4. Car-door-operating mechanism comprising a rotatable operating member, a flexible connection, an equalizing-bar and links connecting the equalizing-bar and the doors, said connection being adapted to lift the equalizer to a locking position on the operating member; substantially as described. 65

5. Car-door-operating mechanism comprising a rotatable operating member, a flexible connection, an equalizing-bar and links connecting the equalizing-bar and the doors, said connection being adapted to lift and support the equalizer in a locking position on the operating member; substantially as described. 70

6. Car-door-operating mechanism comprising an operating member, links and equalizing connecting means for raising the adjacent ends of said links to a point above the axis of the operating member, said links diverging 80 from said point to the doors, when said doors are in closed position; substantially as described. 75

7. Car-door mechanism comprising in combination with the doors, rotatable arm, links 85 and equalizer, means on said arm which directly support the equalizer when the doors are closed; substantially as described.

8. Car-door mechanism comprising in combination with the doors, lifting-chain and segment, a clevis, and means on the segment which take the weight off the chain when the doors are closed; substantially as described. 90

9. Car-door mechanism comprising in combination with the doors and lifting-bars, an 95 equalizer, chain, clevis and segment, and a pin connecting the equalizer and the clevis and adapted to engage projections on the segment; substantially as described.

In testimony whereof I have hereunto set 100 my hand October 18, 1904.

CHARLES A. LINDSTRÖM.
